UNITED STATES PATENT OFFICE.

LYCUS D. PERRY, OF NEW ROCHELLE, NEW YORK, ASSIGNOR TO LUDWIG & COMPANY, OF NEW YORK, N. Y., A CORPORATION OF NEW YORK.

LEVELING DEVICE FOR PIANO KEYS.

Application filed June 3, 1924. Serial No. 717,644.

This invention relates to leveling devices for piano keys and more particularly to a device especially adapted for use on the keys of grand pianos.

5 An important object of the invention is to permit the leveling of the keys after the installation of the keys in the piano.

A further object of the invention is to provide a threaded screw having its lower end arranged adjacent the usual key pin and adapted to be substituted for the latter as the fulcrum means of the key, the threaded member being adapted for vertical adjustment to effect the leveling of the key.

15 Other objects and advantages of the invention will be apparent during the course of the following description.

In the drawings I have shown several embodiments of the invention. In this showing,

Figure 1 is a side elevation of a key embodying the invention, and associated elements, parts being shown in section,

25 Figure 2 is a section on line 2—2 of Figure 1, and,

Figure 3 is a transverse sectional view through the key showing a modified form of leveling screw.

Referring to the drawings the numeral 10 30 designates the usual key frame having a balance rail 11 mounted thereon. The key frame is provided at its rear end with the usual cushion 12 adapted to support the rear end of the key in inoperative position. The 35 usual key 13 is mounted above the balance rail as shown and is provided with a capstan 14 for connection with the operating mechanism of the piano (not shown).

The key 13 is provided substantially centrally thereof with a guide slot 15 adapted to receive a key pin 16 the lower end of which is secured in the usual manner to the balance rail 11. The slot 15 is substantially equal in width to the thickness of the key 45 pin and the latter serves to prevent side motion of the key in operation in the usual manner. The lower end of the slot 15 is restricted as at 17 to snugly fit the key pin 16.

The key 13 is provided either forwardly 50 or rearwardly of the slot 15 and in proximity thereto with a substantially vertical threaded opening 18 to receive a threaded regulating screw 19. The screw 19 is provided with a preferably integral knob or 55 head 20 at its lower end having a rounded

lower face having a rounded lower face adapted to be supported upon a cushion 21 glued or otherwise secured on the upper face of the balance rail as shown. The regulating screw may be provided with a flattened upper end 22 for engagement with a suitable tool for rotating the screw to secure proper adjustment.

In Figure 3 of the drawings I have shown a slightly modified form of regulating screw 60 23. In this form of the device I prefer to use relatively thin threaded wire which may be driven through a previously drilled opening 24 in the key 13. The lower end of the screw is provided with a head 25 similar in 65 construction to the head 20 except that it is formed as a separate piece threaded on the screw 23. In this form of device I also preferably employ the cushion 21 previously described.

The operation of the device is as follows:

The lower face of the head 20 is adapted to contact with the cushion 21 to serve as a pivot point or fulcrum for the key when the forward end of the latter is depressed, the 70 pin 16 serving as a guide to prevent side movement of the key. While the restricted portion 17 of the slot 15 snugly receives the pin 16 the fit between these elements should be sufficiently loose to allow free movement 75 when the key is depressed. I have found that by placing the screw 18 in close proximity to the pin 16, the relative movement between these members is so slight as to cause no binding action, the action of the key being perfectly free. The operation of the 80 form of the device shown in Figure 3 is identical with that previously described.

When installing the keys in pianos, particularly in grand pianos, it has been found 85 practically impossible to provide accurate leveling of the outer ends of the keys regardless of the accuracy of workmanship in manufacturing the individual parts. It is the usual practice to effect the leveling 90 of the keys by a tedious method which requires successive removal and replacing of the keys until the proper leveling is obtained. In the present invention, the keys 95 all may be installed in the piano and leveling of the keys may be readily effected without their removal by turning the screws 18 or 23, depending upon the form of the device employed. The friction between the regulating screw and the threaded opening 100 105 110

in which it is received is sufficient to firmly maintain the screw in any desired adjusted position. It will be obvious that any suitable form of tool may be employed for turning the screws and they readily may be adjusted in a short space of time without removing them from the piano. The rounded heads employed on the forms of regulating screws described provide a smooth contact with the cushion 21 and any slight rearward movement of the heads when the key is depressed, due to the snug fitting of the pin 16 within the restricted opening 17, will be taken up by the rearward sliding of the heads upon the cushions. This relative movement, however, is so slight as to be entirely negligible and does not affect the free action of the keys.

It is to be understood that the forms of my invention herewith shown and described are to be taken as preferred examples of the same and that various changes in the shape, size, and arrangement of parts may be resorted to without departing from the spirit of the invention or the scope of the subjoined claims.

Having described my invention, I claim:

1. In a piano action, a balance rail, a key mounted above the rail and provided with a guide slot having a restricted lower end, a key pin carried by the rail and projecting upwardly through said slot, said pin being snugly received in the restricted portion of said slot, and a vertically adjustable fulcrum pin carried by said key adjacent said key

pin and slidably resting upon said balance rail.

2. A device constructed in accordance with claim 1 wherein said fulcrum pin is provided at its lower end with an enlarged head having a rounded lower face contacting with said rail.

3. In a piano action, a balance rail, a key mounted above the rail and provided with a guide slot having a restricted lower end, a key pin carried by the rail and projecting upwardly through said slot, said pin being snugly received in the restricted portion of said slot, and a vertical fulcrum pin threaded through said key adjacent said key pin and slidably resting upon said balance rail.

4. In a piano action, a balance rail, a key mounted above the rail and provided with a guide slot having a restricted lower end, a key pin carried by the rail and projecting upwardly through said slot, said pin being snugly received in the restricted portion of said slot, a vertical fulcrum pin threaded through said key adjacent said key pin, an enlarged head carried by said fulcrum pin at its lower end and provided with a rounded lower face, and a cushion arranged on said rail, the rounded lower face of said head being adapted to slidably rest upon said cushion.

In testimony whereof I affix my signature.

LYCUS D. PERRY.
